UNITED STATES PATENT OFFICE

1,994,046

APPARATUS FOR PRINTING MUSIC

Leon M. Newbaker, Philadelphia, Pa.

Application December 27, 1929, Serial No. 416,929

6 Claims. (Cl. 33—184.6)

My invention relates to new and useful improvements in an apparatus for printing music, which I term a scriptograph, and has for its object to provide for the proper positioning and aligning of ruled paper upon a platen and the guiding of properly mounted musical characters to make the impressions of said characters upon the paper step by step at the proper elevation relative to the ruling or staves upon said paper.

10 A further object of my invention is to provide a traveling reach bar and mechanism for moving said reach bar up and down relative to the music sheet and also to provide multiple bases slidably supported by said reach bar so as to determine the position of each character upon the staves.

15 A further object of the invention is to provide a series of mountings each of which has a musical character so placed thereon that the impression therefrom will be determined by the mounting.

20 With these and other ends in view, this invention consists in the details of construction as herein shown and then specifically designated 25 by the claims.

25 In order that those skilled in the art to which this invention appertains may understand how to make and use the same, I will describe its construction in detail, referring by numerals to 30 the accompanying drawings forming a part of this application, in which:—

Fig. 1 is a plan view of an apparatus made in accordance with my improvement.

Fig. 2 is an edge view thereof.

35 Fig. 3 is a section at the line 3—3 of Fig. 1.

Fig. 4 is an enlarged section of the guide base head, on line 4—4 of Fig. 1 with the swinging leaf which forms the "Base B" swing back or inward.

40 Fig. 5 is a diagram showing a musical staff and two characters properly mounted and positioned to transfer the impression of the characters thereon to the staff.

Fig. 6 is a detail view of one of the mountings 45 with musical characters thereon.

Fig. 7 is a view similar to Fig. 6 of a larger mounting.

Fig. 8 is a side view of Fig. 6.

50 Fig. 9 is a perspective view of the head block and the component parts thereof with the cross bar broken off.

In carrying out my invention as herein embodied, 10 represents the base or platen of the apparatus, preferably rectangular in shape and 55 of such dimensions as to support the operating

parts and provide for the placing of an ordinary sheet of ruled paper such as is used for printing music. While this base may have its upper surface finished in any suitable manner, I prefer to cover this upper surface with a layer 11 of such material as will give proper friction for holding a sheet of music in place such as rubber.

12 and 13 represent two side bars secured to the base by the feet 14 having the screws 15 passing through suitable holes in said feet and 17 represents two racks formed with or secured to the side bars, each of said side bars having a longitudinal channel 18 formed therein and in these channels, the ends of the cross bar 19 are fitted to slide. This cross bar has depending 10 downward therefrom bearing hangers 20 in which hangers are journalled the shaft 21.

20 22 represents two pinions secured upon the shaft 21 and meshing with the racks so that when the shaft is turned, the pinions will travel in unison along the rack bars carrying therewith the cross bar 19, keeping said bar in perfect alignment as will be readily understood, and for convenience in revolving the shaft 21 the thumb knob 23 is secured upon one end of said shaft.

25 24 represents a head block which is fitted upon the cross bar 19 and adapted to slide longitudinally of said bar and held against accidental displacement by a clutch plate 25 bearing against the forward edge of said bar by the action of the spring 26 mounted in the head. The clutch plate is held on the head block by screws 27 passing through slots and can be actuated by the finger piece 28. This provides for the quick movement 30 of the head block to-and-fro upon the cross bar and for holding said block against accidental displacement in any position it may be set.

35 Formed with or secured to the head block is a guide plate 29 which stands at right angles to the forward surface of the block, thus forming a guide for holders upon which are mounted characters for printing music and this forward surface of the head block, I designated as "Base A", its relation to the operation of the apparatus being hereinafter more fully described.

40 To the guide plate 29 is pivoted as at 30 a swinging leaf 31 which I designate as "Base B", the relation of which to the operations of the apparatus will also be hereinafter more fully described.

45 The heel of the leaf 31 contacts with the plate spring 32, the latter being secured as at 33 to the guide plate so that this leaf may be turned in order that its working surface may be 50 55

brought flush with the working surface of the guide plate, the spring serving to lock the leaf in either its distended position by pressure against the heel of the leaf as shown in Fig. 1 or in its 5 turned-in position by bearing against the flat surface of the leaf after the well known manner of a pen knife blade and spring.

34 represents a spring clip secured to the base in such manner as to readily clamp a sheet of 10 paper upon said base, said paper having music staves 35 lined thereon and 36 is an auxiliary spring clip also secured to the base and having its rear end extending into close proximity to the 15 cut-away turn button 36', whereby the front jaw thereof may be held open by the turn button being turned over the rear end of this clip, thus holding said end in a depressed position.

The object of this is to facilitate the positioning of the paper to be printed upon the base 20 which is accomplished by holding the auxiliary clip 36 out of action as just described, inserting the paper beneath the clip 34 and then swinging the paper as of a center, represented by the hold of the clip 34 thereon until it has been properly 25 aligned and then releasing the auxiliary clip 36 so that it may take hold upon said paper thereby firmly holding the latter against any displacement during the operation of printing thereon.

These clips may be of any desirable construction 30 and therefore I have not shown any detail of construction thereon.

37 represents pointers telescoping into the tubes 38 and held in any position therein by the screws 39, said tubes being pivoted as at 40 to the 35 base so that the pointers may be swung out of action or into action, the latter position being shown in Fig. 1.

When these pointers have been properly adjusted in their tubes, they serve to indicate the 40 proper position of the paper upon the base, which position is indicated by the contact of the ends of the pointers with certain of the lines, preferably the top line of the top staff of the paper ruling.

45 From the foregoing description, it will be seen that the cross bar may be moved up or down upon the side bars by the proper revolving of the shaft 21, thus bringing the guide plate and the bases A and B into proper relation with the 50 staves ruled upon the paper which proper relation will be indicated by the pointer 41 carried by the guide plate 29 and this position will be determined upon the scale 42 by the pointer 43 carried by said cross bar, the plate upon which 55 said scale is inscribed being either formed with or secured to the side bar 12.

The scale 42 is provided with a number of main graduations and intermediate graduations and is further divided into groups of graduations 60 44 indicated by longer lines or by the coloring of certain lines of the graduations and these groups of graduations correspond to the staves and groups of staves upon the ruled paper so that the operator of the apparatus may readily determine by casual observation which line of a particular staff is being indicated by the pointer 43.

The cross bar 19 has upon the upper surface thereof inscribed the scale 45 of relatively fine 65 graduations and also has inscribed thereon the scale 46 of coarser graduations, which are arbitrary and represent the spacing of musical characters, and the head block has an opening 47 therein through which these scales appear as the block is slid back and forth upon the bar and

projecting into this opening is a pointer 48 which registers with the finer scale and also a pointer 49 which registers with the coarser scale, thus enabling the operator to readily and accurately determine the position of the head block which determines the position right and left in which the characters will be printed upon the staves of the ruled paper.

The musical characters utilized for accomplishing the printing of music upon the staves 10 of properly ruled paper are mounted upon the holders 50, 50A and these holders as shown in Figs. 5, 6, 7 and 8 are of different widths, each however, being of equal length and usually of the same thickness and are adapted to be guided 15 by the guide plate 29 and the base A or the base B and the characters mounted upon said holders are so positioned thereon as to bring each of them into proper position upon one of the staves ruled upon the paper when properly positioned 20 by the guide plate and either base A or base B, as for instance, notes having long stems being mounted upon the wide holders while the notes having the short stems being mounted upon the narrow holders, the wide holders are guided by 25 the guide plate and the base A while the narrow holders are guided by the guide plate and base B, thus permitting the printing of a great variety of characters from a less number of holders without the loss of time and annoyance necessary 30 to move the cross bar through greater distances for changing the positions of the characters upon the paper.

When a short stem note is to be printed, the leaf 31 is swung out to the position shown in 35 Fig. 1 and used as base B and the cross bar moved until the pointer 41 indicates the line or the space upon or in which the head of the character is to be printed when the operator simply picks up the holder with the proper 40 character thereon and slides it downward, keeping one face and one edge in contact with the guide plate and base B, which will print the character in accurate position upon the staff. The same result will be had when the wide holders 45 are used by simply closing in the leaf 31, thus permitting the use of base A for the position of the holder relative to the staff being printed upon.

It is to be understood that where notes are 50 to be printed with the stems turned upward, the holders carrying such characters are turned in the proper position and when the stems are to extend downward, said holders are reversed.

It is also to be understood that the pointer 41 55 may be made adjustable upon the head block by being pivoted thereto so as to be slightly raised or lowered to accommodate different thicknesses of paper to be printed upon.

In practice, the various characters used in 60 music, such as clefs, rests, bars, figures indicating time and the like, letters indicating fingering, silent measures, numbering of the pages and the like, as well as notes, may be readily printed in proper positions, as before described, thus providing for the use of all characters used in printing music.

Of course I do not wish to be limited to the 65 exact details of construction as herein shown, as these may be varied within the limits of the appended claims without departing from the spirit of my invention.

Having thus fully described my invention, what I claim as new and useful is:—

1. In an apparatus for printing music, a platen 75

on which a sheet of paper is to be mounted, said sheet of paper having musical staves delineated thereon, means for holding said paper on the platen, a head block, means for moving said head block crosswise and lengthwise of the platen to vary the position of said head block relative to the musical staves, a fixed base carried by said head block, and a swinging base also carried by said head block, said bases being selectively usable for guiding holders carrying musical characters so as to properly position said characters upon the staves.

2. In an apparatus for printing music step by step, a platen to receive a paper having musical staves delineated thereon, a movable head block means to move said head block transversely and longitudinally over said platen, a fixed base carried by said head block, and a swinging base also carried by said head block, said bases being selectively used according to the musical characters to be printed.

3. The structure set forth in claim 2, in combination with means to indicate the position of the head block and therefore the bases relative to the paper on the platen longitudinally of the latter, and means to indicate the position of said head block and said bases relative to the paper on the platen transversely of said platen.

4. In an apparatus for printing music, the

combination of a platen, a movable head block, means to move said head block over said platen both longitudinally and transversely thereof, a fixed base carried by said head block for guiding holders carrying printing characters, and a pivoted base for selective positioning in front of the fixed base and to one side thereof, said pivoted base being used for guiding holders carrying printing characters when said pivoted base is swung to the position in front of the fixed base.

5. An apparatus for printing music, comprising a platen, means for positioning and holding a sheet of paper upon said platen, said paper having musical staves delineated thereon, a head block, means to support said head block for longitudinal and transverse movement over said platen, a fixed base carried by said head block, a swinging base also carried by said head block, said bases being selectively usable for guiding holders carrying musical characters whereby said characters may be properly positioned relative to the musical staves, and mechanical means for moving the head block and its component parts longitudinally of the platen.

6. The structure set forth in claim 5, in combination with mechanical means for guiding said block in any position transversely of the platen.

LEON M. NEWBAKER.
